UNITED STATES PATENT OFFICE.

CARL MORIGGL, OF ARBON, SWITZERLAND, ASSIGNOR TO THE FIRM OF ADOLPH SAURER, OF ARBON, SWITZERLAND.

RIBBON-LOOM.

1,183,583.

Specification of Letters Patent. Patented May 16, 1916.

Application filed November 14, 1910. Serial No. 592,307.

To all whom it may concern:

Be it known that I, CARL MORIGGL, a subject of the Emperor of Austria-Hungary, and a resident of Arbon, Switzerland, have 5 invented certain new and useful Improvements in Ribbon-Looms; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 This invention relates to improvements in ribbon looms and has for its object to provide a loom in which the objectionable friction and tension of the threads are avoided and in which the threads are prevented from 20 sticking to each other when the shed is being formed.

Instead of the ordinary straight leaves which move in a straight line, the loom constructed according to the present invention 25 is provided with circular leaves, the radius of the curve being equal to the distance from the leaves to the point where the weft threads are inserted, said leaves being adapted to turn on a pivot, the axis of which is 30 at said point where the weft threads are inserted.

The tension of the warp threads in passing from the upper shed to the lower shed, and vice versa, is compensated by movable 35 whips. To prevent the threads from sticking to each other and being taken into the wrong shed, a finger is provided which enters the shed and separates the threads of the shed before the weft threads are inserted. 40 Lastly, a guide for the shuttle is provided which oscillates the shuttle about a given axis which is in front of the point where the weft threads are inserted. The thread guide is situated at about this point, 45 so that the distance through which the guide moves is smaller than that moved through by the shuttle itself, and in consequence, only so much thread is drawn off from the spool as is necessary for the weft.

50 In shuttles in which the thread guide and the shuttle travel through the same distance, more thread is drawn off the spool than is necessary for the weft, and the excess thread has to be stretched which causes consider-

able friction of the thread against the part 55 which does the stretching.

In the accompanying drawings, Figure 1, is a side elevation of the loom partly in section, Fig. 2 is a section on line 2—2 of Fig. 1. Fig. 3 is an elevation, and Fig. 4 a plan 60 view, partly in section, of the device for separating the warp threads. Fig. 5 is an elevation, and Fig. 6 is a plan view of the means for oscillating the shuttle. Figs. 7, 8 and 9 are detail views of parts serving the 65 latter purpose. Fig. 10 is a detail view of the feed for the finished ribbon, and Fig. 11 is a detail view of the reed actuating mechanism.

The loom is provided with two leaves as 70 1 and 2, in which are fixed the heddles 4 and 5 supporting the warp threads 3, 3. One series of warp threads is guided through the heddles of leaf 1 and the other series through those of leaf 2. Both leaves are circular 75 in shape, their radius being equal to the distance from point 6, where the weft threads are inserted, to the leaves. The leaves are supported on arms 7 and 8 which are linked to them and turn on shafts 9 which are supported in the frame of the loom on both sides of the way for the ribbons. Oscillation is imparted to the leaves by a crank-shaft 10 having cranks 11, 12 which are connected to the leaves by pitman rods 13 and 80 14. The cranks are at 180° to each other to effect the alternating up and down movement of the leaves when forming the shed.

15 and 16 designate two guiding rollers, the roller 15 being journaled in fixed bearings, and roller 16 is pressed against the roller 15 and the ribbon by springs 16'. Stationary guide as 17 is also provided for the ribbon. The roller 15 is rotated by means of a worm-wheel 15' on the shaft of said 90 roller, which wheel engages a worm 56' on a shaft 56. A lever 57, (Fig. 10) is pivoted on the shaft 56 and carries a spring urged pawl 58 which engages a ratchet wheel 59 mounted on said shaft 56. The lever 57 is 100 connected by a rod 60 to an oscillatory lever 62 which is pivoted at 61 on the frame of the machine (Fig. 11). Motion is imparted to the lever 62 by means of a roller 64 which engages a groove 63 formed in the end of a 105 roll 36 fixed on the shaft 10. A second spring-controlled pawl 65 engages the ratchet wheel 59 and prevents shaft 56 from

being turned in the wrong direction. The object of this mounting is to insure that the length of the warp threads will always be the same whatever the position of the leaves 6 may be, and consequently, friction of the threads in the heddles is prevented.

Whips 18 and 19 serve to compensate the tension of the warp threads when the shed is being formed. Apparatus for the same 10 purpose is known, but in these, all the warp threads are guided over one whip which under the effect of a pull back spring tensions the series of warp threads supported by each of the leaves. In order to do away with 15 this drawback each series of warp threads in the present loom is guided over a separate whip, and both the whips turn on a common pivot 20. The angles through which the whips turn correspond to the amount of 20 tension in the threads when changing the shed. The whips are approximately rectangular frames and the whip 18 is free to move within the whip 19. Both whips are connected at their lower ends to a cross piece 25 22 which is connected centrally to a spring 21, the tension of which is regulated by means of a rod 23 and a nut 24.

The warp threads 3, 3 are guided through holes in the upper part of the whips 18, 19, 30 under shaft 20 to a shaft 25. Pins 26 are suspended from every warp thread and by their weight compensate tension in the several threads and also serve as warp stops. The pins after falling down may be raised 35 again by a lever 27. When the threads are raised or lowered by the leaves 1 and 2 to form the upper or lower shed, the threads passing from the leaves through the whips and under shaft 20 allow a rocking of the 40 whips which are on a single shaft, and under the tension of a single spring. The lengths of the threads from the leaves to the whips are always the same, and consequently the tension of the threads is also the same. 45 When, for example, the threads are lifted from the lower into the upper shed, the spring 21 is able, when the threads are in the center of the shed, to turn whip 19 in the direction of the arrow, Fig. 1. When 50 the threads are raised further into the upper shed, tension is put on them again and they pull the whip 19 back to the left against the tension of spring 21. When the threads are moved from the upper shed into the lower 55 shed, spring 21 will pull the whip 18 to the right when the threads pass through the center in the lower shed, and the whip 18 will be pulled back to the left. It follows that the tension of the threads passing 60 through one of the whips is compensated independently of the compensation of the tension of those passing through the other whip. The cross piece 22 during the alternating action of spring 21 on the whips, 65 pivots alternately on its point of attachment

to the one and to the other whip, while, when the threads are in the center of the shed the action of the spring is the same on both whips. This warp tension regulating mechanism *per se* is not herein claimed as it has been made the subject matter of a separate Patent, No. 1,104,377, granted July 21, 1914 on a divisional application. 70

It often occurs that when the shed is opened some of the warp threads stick to others, in consequence of knots or rough parts which they may have, and are taken with them in the wrong direction, get into the way of the shuttle and are broken by it as it passes through the shed. This is avoided by the device shown in Figs. 3, 4, and 75 5 in which a movable member is made to pass through the shed laterally and thereby separates the threads. In the form illustrated this device consists of a pivoted 80 forked finger 28 carried by a shaft 30 arranged laterally to the reed 29. The shaft 30 has teeth 31 (Fig. 4) which are engaged by a toothed arm 33 carried by a shaft 32. A roller 34 on the arm 33 engages a groove 90 35 in the roll 36 fixed on shaft 10 by which the fork 28 is oscillated so as to make it enter the shed laterally and move toward the reed 29 before the weft is inserted. When in consequence of any obstacles, say 95 knots or roughened parts, a thread sticks to the adjacent one when the shed is opened and is taken, say into the upper shed instead of moving into the lower shed, fork 28 on its inward movement will separate 100 these threads. The weft is then inserted between the prongs of the fork 28, and then the latter is withdrawn out of the shed.

The shuttle comprises a segmental slide 37 (Figs. 6 and 7), and a holder 38 in which the weft spool 39 is mounted and a thread guide 40 made integral with the holder 38, is provided with a threading eye 41 which is near the point 6 where the weft is inserted, that is, near the reed 29. The shuttle is 105 adapted to move to and fro in an annular guide 42 which is interrupted at 43 to allow the warp threads to pass when moving up and down in order to open or close the shed. Movement is imparted to the shuttle by a 110 lever 47 mounted on a shaft 46 which has a lever 45 carrying a roller which engages a groove 44 in the roller 36. Pivoted on lever 47 is a coupling member 48 (Fig. 7) having curved projections 49 and 50 and a 115 roller 51 engaging a slot 52 of a projection 53 beneath guide 42. The slot 52 has an upper and a lower part connected by an incline. 120

The coupling member 48 serves to connect the slide 37 to the lever 47 by one of the projections 49, 50 engaging recesses 54, 55 of slide 37, so that the slide is bound to follow the movement of lever 47. The axis of the guide 42, *i. e.* the shaft 46 is in front of point 6 and the reed 29, in other words 125 130

it is on the opposite side of the point of from the heddles. The eye 47 of thread guide 40, being nearer to shaft 30 than eye 39, moves through a distance less than the latter. The distance of shaft 30 from point 6 where the weft is inserted is such that the weft passing through eye 47 is not taken unnecessarily beyond the shaft 30, and the only sufficient fibrous is taken from the 10 speal as is necessary for forming the weft.

The to and fro movement of the heddles is caused by the action of the lever 45 caused by the projection 49 which is caused by the left. This is shown in Fig. 11, that the 15 roller 31 is in the position shown in Fig. 10 and thus turns the eye 47 to the right so as to make projection 49, which is caused by the slide 32, which is caused by the weight, from lever 45, so that the roller 31 20 moves in the direction of the arrow and the projection 36 is out of the way of the 15 warp threads. When the lever 45 moves to the right, the roller 31 goes to the outer part of shaft 30 and vice versa, so that the coupling member 46 is withdrawn from the projection 49 and engaged with the lever 45, so that the projection 49 now being in the inner position and clearing the warp threads.

30. The roller 31 and the shaft 30, when actuating it, are shown clearer in Fig. 11. The roller is probably mounted on a pin 61 and is oscillated by means of a spring 67 which is connected to the shaft end in the 35 lever 62, which impacts in contact to the roller guide rollers, and is rotated by the roller 31 as hereinafter described.

I claim:

1. In a ribbon loom, a plurality of leaves for forming the shed of the warp threads, mounted to rock about axes disposed in the line of insertion of the weft threads into the shed, the centers of the leaves being disposed in said line of insertion, heddles disposed to the leaves, and means for varying 40 the distance between the point where the warp threads are drawn off and the leaves.
2. In a ribbon loom, a plurality of leaves for forming the shed of the warp threads, 45 mounted to rock about axes disposed in the line of insertion of the weft threads into the shed, the centers of the leaves being disposed in said line of insertion, heddles disposed to the leaves, and means for varying 50 the distance between the point where the warp threads are drawn off and the leaves.
3. In a loom, a plurality of heddles for forming the shed of the warp threads, mounted to 55 rock about axes disposed in the line of insertion of the weft threads into the shed, the centers of the heddles being disposed in said line of insertion, and means for varying the distance between the point where the 60 warp threads are drawn off and the heddles.

4. In a loom, a device for separating the warp threads which stick to each other when the shed is opened, comprising a finger, and means for moving the finger to pass laterally through the shed and toward the reed 70 of the loom.

5. In a loom, a device for separating the warp threads which stick to each other when the shed is opened, comprising a pivoted member, and means to move the latter 75 into and out of the shed.

6. In a loom, a device for separating the warp threads which stick to each other when the shed is opened, comprising a pivotally mounted forked member movable into 80 and out of the shed, and means to pass the weft threads through said forked arm.

7. In a loom, leaves for forming the shed of the warp threads, a shuttle for passing the weft thread through the shed when the shed is open, a curved guide for the shuttle, a pivoted member for separating the warp threads which stick to each other when the shed is opened, a cam member having two separate cam faces, means engaging with one of said faces for reciprocating said shuttle and means for engaging with the other of said faces for operating said shed opening member.

8. In a ribbon loom, the combination of 95 leaves for forming the shed of the warp threads, a reed, a shuttle for passing the weft thread through the shed when the shed is open, a curved guide for the shuttle having its axis closely adjacent to one side of the reed, a guide eye carried by said shuttle and arranged closely adjacent to the opposite side of the reed, and means for reciprocating said shuttle along said curved guide whereby said guide eye moves through a 100 distance but slightly greater than the width of the operative portion of said reed.

9. In a ribbon loom, the combination of 105 leaves for forming the shed of the warp threads, a shuttle for passing the weft thread through the shed when the shed is open, means between said shuttle and the inserted weft and having a movement substantially in the direction of the length of the warp threads for separating the warp 115 threads which stick together as the shed is opened, and a curved guide for the shuttle, said shuttle having a thread holder and a guide eye disposed nearer to the center of oscillation of the shuttle than to the thread 120 holder.

10. In a ribbon loom, the combination of 125 leaves for forming the shed of the warp threads, a shuttle for passing the weft thread through the shed when the shed is open, a member movable into the shed to open the latter and independent of said shuttle, and a curved guide for said shuttle, said shuttle having a thread holder and a guide eye disposed nearer to the center of 130

oscillation of the shuttle than to the thread holder.

11. In a ribbon loom, leaves for forming the shed of the warp threads, a movable member for entering the shed and separating the threads which stick together, a shuttle for passing the weft thread through the shed when the shed is opened, a curved guide for the shuttle, means for reciprocating the latter about an axis adjacent to, but in front of, the point of separation of the

warp threads, and a guide carried by said shuttle and having an eye therein adjacent to said shed opening member.

In testimony that I claim the foregoing 15 as my invention, I have signed my name in presence of two subscribing witnesses.

CARL MORGGL.
